ELECTRICAL SAFETY DETONATOR

Gerald V. Spickard, Houston, Tex., assignor to Schlumberger Well Surveying Corporation, Houston, Tex., a corporation of Texas

Filed Feb. 17, 1964, Ser. No. 345,242

2 Claims. (Cl. 102—28)

This invention relates to electrical safety detonators for use in well bores in detonating explosive shaped charges and, more particularly, relates to detonators which are useful where exposed to excessive well bore pressures and temperatures.

In general, well bore perforating apparatus using shaped charges may be conveniently divided into the so-called carrier-type and the so-called capsule-type apparatus. The relative advantages and disadvantages of the two types need not be described herein, it being sufficient to note that the present invention has a particularly useful application with capsule-type well perforators, such as that shown in Patent No. 2,981,185.

Generally, in capsule-type perforators, shaped charges are individually encapsulated so as to be waterproof. The shaped charges are either linked together to form a chain-like assembly of charges or arranged on a mounting, such as a strip, for lowering into a well bore which is to be perforated. A waterproof blasting cord for detonating the shaped charges is secured to the rear of each charge and a waterproof electrically operated detonator or blasting cap is provided for igniting or detonating the blasting cord. A blasting cap or detonator typically includes a primer explosive which is ignited when an igniter wire is heated by an electric current. The primer explosive, in turn, sets off a booster explosive which develops sufficient energy to detonate the less-sensitive explosive in the blasting cord. Accordingly, to detonate the shaped charges, an electrical current is passed from the surface of the ground through electrical conductors of a cable to the detonator in the well bore. Passage of current through the blasting cap igniter then initiates a chain reaction which subsequently detonates the shaped charges.

It will be appreciated that the components of such capsule perforators, e.g., the blasting cap, blasting cord and encapsulated shaped charges, are subjected to the ambient conditions in the well bore and that these components will generally fail, or at best not function properly, should well fluids leak into them before they are operated. Accordingly, considerable effort has been expended in devising fluid-tight components to keep pace with the higher pressures and temperatures corresponding to the ever-increasing depths to which oil wells are currently being drilled.

A particular source of failure heretofore has been caused by well fluids under pressure leaking into a sealed detonator at the point where the insulated electrical leads enter the sealed detonator case. Such leakage is generally attributed to the inability of common electrical insulations to withstand high pressures without leaking as well as the difficulty in maintaining a fluid seal between the insulation and the metal conductor itself. As a consequence, it has been found that conventional detonators give serious trouble in service where ambient well conditions exceed 8,000–10,000 p.s.i.g. and approximately 200° F.

It is, therefore, an object of this invention to provide a new and improved detonator means for well bore shaped charge perforators which are capable of reliable operation at high pressures and temperatures.

Another object of this invention is to provide new and improved detonator means which have a high-pressure fluid-tight seal.

2

It is a further object of this invention to provide new and improved detonator means with positive sealing against fluid leakage around electrical conductors entering the detonator means.

5 The detonator means of the present invention is comprised of a hollow metal blasting-cap case having an open end and arranged to receive a conventional electrically ignited blasting cap which has at least one electrical conductor connected thereto. A metal closure member arranged for fluid tight sealing in the open end is provided with a passage therethrough for sealingly receiving a metal conductor pin which is electrically insulated by a surface treatment.

10 When the detonator means is assembled, the conductor pin is sealingly engaged within the closure member passage and a blasting cap conductor is internally connected within the case to the inner end of the conductor pin. The outer or external end of the conductor pin is adapted for subsequent connection to a source of electrical energy.

15 The novel features of the present invention are set forth with particularity in the appended claims. The present invention, both as to its organization and manner of operation together with further objects and advantages thereof, may best be understood by way of illustration and example of certain embodiments when taken in conjunction with the accompanying drawings in which:

20 FIG. 1 is a sectional view of a preferred embodiment of a detonator constructed in accordance with the principles of the present invention; and

25 FIG. 2 is an enlarged view of a portion of FIG. 1.

30 As seen in FIG. 1, a hollow blasting cap case 10 is formed of metal with sufficient thickness and strength to withstand high pressures encountered in a well bore. Case 35 10 has a centrally located longitudinal cavity or bore 11 which is closed at one end by a transverse web 12 and has an opening 13 at the other end. The opening 13 of cavity 11 is counterbored, as at 14, to form an intermediate annular shoulder 15 facing the opening.

35 A conventional electrically ignited blasting cap 16 is disposed within cavity 11 with its nose in close proximity to web 12 and its electrical leads 17, 18 extended toward opening 13. A metal closure member 19 is sized for reception in counterbore 14 and has two longitudinal passages 20, 21 extending therethrough. Although closure member 19 could be sealed by soldering and the like, a peripheral groove 22 is provided around closure member 19 to receive an O-ring 23.

40 As seen in FIGS. 1 and 2, the passages 20, 21 through closure member 19 are counterbored, as at 24 and 25, to provide intermediate outwardly facing shoulders 26, 27. Metal pins 28, 29, of a metal which conducts electricity easily, are sized for reception in passages 20, 21. Each of these conductor pins has an intermediate enlarged-diameter portion 30, 31 which respectively have peripheral grooves 32, 33 for receiving O-rings 34, 35. Although other means for connecting could be provided, it is preferred to form short axial passages 36, 37 into each end of conductor pins 28, 29 for receiving the ends of electrical conductors.

45 It will be understood, of course, that conductor pins 28, 29 must be electrically isolated from one another as well as from closure member 19 and receptacle 10. Accordingly, it is preferred to make conductor pins 28, 29 of aluminum and, as indicated by the dotted markings on

50 pin 29 in FIG. 2, to hard-anodize the coextensive outer surfaces of conductor pins 28, 29 that could be brought into contact with closure member 19. It has been found that for the relatively low voltages customarily used in the perforating art, such hard-anodizing to a depth of about 0.001–0.002 inch provides an excellent electrical insulation or dielectric on the surfaces of the conductor pins

while still permitting transmission of electricity through the central portion of the body of the pins. Accordingly, it will be appreciated that by anodizing the conductor pins 28, 29, only the annular spaces around the pins require fluid sealing and that now a high-pressure O-ring sealing member can be successfully used to seal off this space.

Although it is not essential, it is nevertheless preferred to make closure member 19 also of aluminum and hard-anodize at least its outer surfaces to provide a second insulating surface should one of the conductor pins be inadvertently shorted to the closure member. The use of aluminum will also permit the surfaces of passages 20, 21 to be anodized should further insulation be desired.

At the opposite end of case 10 from closure member 19, an axial recess 40 is provided for receiving either the end of a detonating cord or, where necessary, a conventional fluid-tight encapsulated booster charge 41. Booster charge 41 is customarily provided with a recess 42 into which the end of a detonating cord (not shown) is inserted and secured while assembling the perforating apparatus. The booster charge 41 is disposed within recess 40 with its inner end being separated from the inner end of blasting cap 16 by only the transverse web 12 of case 10. Thus, it will be appreciated that when blasting cap 16 is detonated, the explosion thereof will perforate web 12 and detonate booster charge 41.

In assembling the detonator of the present invention, conductor pins 28, 29 are sealingly disposed within passages 20, 21 of closure member 19, and, as seen in FIG. 2, the exposed ends of blasting cap electrical leads 17, 18 are inserted into axial passages 37 in the inner ends of conductor pins and crimped and fixed in place, as at 39. Similarly, short lengths of electrical conductors 42, 43 are inserted into the axial passages 36 in the outer ends of conductor pins 28, 29 and crimped and fixed in place as shown at 38. The bared terminal ends of conductors 42, 43 are then temporarily twisted together, as at 44, to ensure that stray electrical charges will not prematurely detonate blasting cap 16. O-ring 23 is disposed within peripheral groove 22 of closure member 19, and the sub-assembly inserted into cavity 11 of case 10.

The remaining terminal portion of counterbore 13 is then filled with electrically nonconductive plastic 45, such as an epoxy, to secure conductor pins 28, 29 and closure member 19, as well as to prevent well fluids from contacting the outer ends of conductor pins 28, 29.

The booster charge 41 is inserted into axial recess 40 at the opposite end of receptacle 19 and similarly sealed in place with a plastic material 46.

Although anodized aluminum is the preferred material for conductor pins 28, 29, similar results could be obtained with other metal-surfacing processes, such as phosphating, where such treatment of an electrically conductive metal will produce an electrically nonconductive surface around the pin.

Accordingly, it will be appreciated that the new and improved detonator of the present invention is capable of withstanding the extreme pressures and temperatures encountered in deep well bores. The electrical conductors are positively fluidly sealed as well as electrically insulated in such a manner as to provide a new and improved detonator capable of withstanding high well temperatures and pressures without leaking fluids which otherwise would short electrical leads and deactivate the blasting cap.

While particular embodiments of the present invention have been shown and described, it is apparent that changes and modifications may be made without departing from this invention in its broader aspects and, therefore, the aim in the appended claims is to cover all such changes and modifications as fall within the true spirit and scope of this invention.

What is claimed is:

1. In a detonator including a hollow case with an open end; an electrically-ignited blasting cap disposed within said case; and a metal closure member sealingly closing said open end against entry of fluid and having at least one passage extending therethrough, the improvement comprising: an electrically-conductive metal conductor member providing an electrical connection between said blasting cap and the exterior of said closure member and having a shoulder abutting said closure member and peripheral surface portions received in complementary surface portions of said passage, at least one 10 of said metal conductor and closure members being of aluminum and having its surface portions anodized to provide electrical insulation between said members; and seal means for pressure sealing said conductor member in and relative to said closure member including an annular sealing ring sealingly engaged between said metal conductor and closure members.
2. In a detonator including a hollow metal case with an open end and an electrically-ignited blasting cap disposed within said case, the improvement comprising: a 15 metal closure member having at least one passage extending therethrough and sealingly engaged with said case to close said open case end against entry of fluids, said passage having an outwardly-facing shoulder intermediate its ends; an electrically-conductive metal conductor member extending through said passage into said case and electrically connected to said blasting cap, said conductor member having an enlarged diameter portion complementarily received in the outer portion of said passage and adapted to engage said outwardly-facing shoulder, at least one of said metal conductor and closure members being of aluminum and having its co-extensive surface portions anodized to provide electrical insulation between said members; and means for fluidly sealing said metal conductor member relative to said closure member consisting of an annular sealing ring disposed in said outer passage portion and sealingly engaged between said closure member and said enlarged diameter portion of said metal conductor member.
